Inventor:

Ferdinand Lindner.

UNITED STATES PATENT OFFICE.

FERDINAND LINDNER, OF DAYTON, OHIO.

IMPROVEMENT IN APPARATUS FOR MAKING BUTTON-HOLES.

Specification forming part of Letters Patent No. **58,651**, dated October 9, 1866.

To all whom it may concern:

Be it known that I, FERDINAND LINDNER, of the city of Dayton, in the county of Montgomery, in the State of Ohio, have invented a new and Improved Button-Hole Regulator; and I do hereby declare that the following is an exact description thereof, reference being had to the accompanying drawings, making a part of this specification, in which—

Figure 1 is a top view of the button-hole regulator. Fig. 2 is a side view of the same. Fig. 3 is an under-side or bottom view of the same. Fig. 4 is a section of line A B. Fig. 5 is a section of line C D.

Similar letters of reference indicate corresponding parts in the several figures.

The object of this invention is to secure and firmly hold the cloth or any other fabric between the jaws of an instrument constructed out of steel or any other material while a button-hole is being worked, preventing the cloth or fabric from slipping, and also from being soiled between the thumb and finger of the workman, and also to regulate the needle and guide the thread, making the seam perfectly straight on the inner and outer side of the fabric.

To enable others skilled in the art to understand my invention, I will describe its construction and operation.

Fig. 2 represents a side view of the button-hole regulator with the jaws open. The upper jaw, A, is round on top and concave on the under side, as seen at *a*, and is a continuation of the bow-spring H. The under jaw, B, is self-adjustable, rounded on top, as seen at *b*,

so as to fit into the concave *a* in upper jaw, A. The object of this is to prevent the fabric from slipping, as it would be more likely to do if the inner surface of the jaws were flat.

The under jaw, B, is composed of steel and connected with the bow-spring H by means of the hinge or joint J, by which it adjusts itself to the thickness of the fabric, causing the pressure to be equal the entire length of the button-hole.

The jaws A and B are opened by means of the levers D D, secured to the plates E by the pins *d d*. By pressing the handles or thumb-pieces G G the levers D D are forced out against the inside of the bow-spring H at *k k*, causing the jaws to open, as seen in Fig. 2.

The small semicircular plates F are placed inside the bow-spring H, for the purpose of securing the levers D D and forming a fulcrum upon which the levers D D act when the pressure is on the handles G G. The orifice L in the bow-spring H is for the levers to pass through.

Having described my invention, what I claim as new, and desire to secure by Letters Patent, is—

A button-hole regulator made of steel or any other suitable material, having the jaws A B, bow-spring H, levers D D, and handles G G, as herein described, and for the purposes set forth.

FERDINAND LINDNER.
